UNITED STATES PATENT OFFICE

LEOPOLD M. REBEL, OF PARIS, FRANCE, ASSIGNOR TO ISABEY-PARIS, INC., OF NEW YORK, N. Y., A CORPORATION OF DELAWARE

DESIGN FOR A BOX

Application filed August 20, 1929. Serial No. 32,466. Term of patent 7 years

To all whom it may concern:

Be it known that I, LEOPOLD M. REBEL, a citizen of Republic of France, residing at 43 Rue du Colisee, Paris, France, have invented a new, original, and ornamental Design for a Box, of which the following is a specification, reference being had to the accompanying drawing, forming a part thereof.

The drawing shows a perspective view of my new and ornamental design. The dominant feature of the design consists in the particular surface ornamentation shown.

I claim:

The ornamental design for a box substantially as shown and described.

LEOPOLD M. REBEL.
